SLING

Charles M. Zerr, Independence, Mo., assignor to
 Union Wire Rope Corporation, Kansas City,
 Mo., a corporation of Missouri

Application June 23, 1947, Serial No. 756,359

7 Claims. (Cl. 57—142)

1

This invention relates to the art of rope making including slings, and particularly wire cables and slings fashioned therefrom, the primary aim being to provide a sling capable of being formed by machines presently used in the industry and having looped ends formed by a novel splicing structure.

The most important object of this invention is the provision of a sling wherein the plurality of laid up ropes forming the cable body are rebent upon themselves to form a loop and then twisted individually about corresponding ropes of the standing part of the cable to form a neat appearing, strong and smooth splice.

Another important object of this invention lies in the manner in which the wires, the strands, and the ropes of the cables as well as the splice per se are laid up in alternate directions of twist.

A further important object of this invention is to provide a sling loop splice having all the ropes of the rebent end twisted in the same direction about the ropes of the standing part of the body of the sling.

A still further object of this invention is the provision of a sling having splice seizing capable of effectively covering and binding in place the ends of the several strands of the splice, which seizing is formed either of wire having a coating of fusible material that integrates upon application of heat or a coating effectively applied without the employment of heat.

Many minor objects will be made clear or become apparent during the course of the following specification, reference being had to the accompanying drawing, wherein:

Figure 1 is an elevational view of a sling made in accordance with the present invention, parts being shown in an unfinished state for clearness.

Fig. 2 is an enlarged fragmentary, perspective view thereof; and

Fig. 3 is a fragmentary schematic view thereof showing the manner of forming the splices.

It is well appreciated by those skilled in this art that wire cables and slings formed therefrom may be made in numerous ways, particularly with respect to the size, number and method of twisting and braiding of the individual units.

The smallest unit utilized in forming the cable is generally referred to as a length of wire. For purposes of illustration, a total of 19 wires are wound or laid together to create what is called a "strand." These 19 wires are designated by the numeral 10, shown especially at one loose end in Fig. 2. The procedure used in so twisting the wires 10 into a strand is commonly referred to as "laying."

Strands 12 in desired numbers as later specified are used to produce ropes and, in turn, 60 length has been formed. These ends generally

2

these ropes in desired numbers as hereinafter mentioned form the cable.

Generally speaking, wire rope is laid up in either a "regular left lay," "regular right lay" or what is termed "Lang lay." In the drawing, the wires 10 are laid to the left, whereas the strands 12 formed thereby are laid to the right to create the regular right lay rope 14. There are three of these strands in each rope 14. This left lay of the wires 10 and right lay of the strands 12 is clearly shown at the untwisted or broomed out ends in Fig. 2. The direction of relative lays may be reversed from the positions as just set forth above and as specified in the following description.

15 A cable broadly designated by the numeral 16 is then formed by laying the ropes 14 to the left, presenting the same directional lay for the wires 10 and the cable 16. It is this cable 16 that forms the body (generally designated 18) of the sling broadly referred to by the numeral 20.

20 Cable 16 is then cut to the desired length and the ends rebent upon themselves to present loops 22. A seizing 24 is placed about the cable 16 spaced from such rebent ends and the ropes 14 are unlaid back to seizing 24.

25 As illustrated, there are not only three strands 12 to produce ropes 14, but three ropes 14 are used to make cable 16. These quantities may 30 well be varied depending on the use intended for sling 20 in the same manner as varying the 19 wires 10 of the strands 12. However, for best results, it is preferable to utilize either 2, 3 or 4 of strands 12 and either 2, 3 or 4 of ropes 14. 35 The strands and ropes so twisted will lay in close juxtaposition whereas when 5 or more strands or ropes are laid, gaps and spaces will be present between the individual units.

40 The three unlaid ropes 14 extending from seizures 24 to the free ends of cable 16 are then woven into the standing part of body 18 to present splices 26. These individual ropes 14 at the end of sling 20 are each separately twisted about a respective one of the ropes 14 of the 45 standing part of body 18 and the lay is to the right or opposite to the lay of ropes 14 to form cable 16.

45 In Fig. 3 the three unlaid ropes 14 of the loop 22 are designated by the letters "a," "b" and "c" and the ropes 15 of the standing part of body 16 are referred to by letters "d," "e" and "f." It is clear that rope a is twisted about rope d, rope b about rope e and rope c about rope f. One of these individual twists of the corresponding ropes 14 in splices 26 is clearly shown in Fig. 2 and designated by the numeral 28.

50 The ends of the ropes 14 of loops 22 are clipped relatively close to body 16 at the innermost end of splices 26 when a splice of sufficient length has been formed. These ends generally

designated by the numeral 39 and constituting the three strands 12 of each rope 14 are covered by seizing 32.

Seizing 32 comprises a length of wire 34 having a coating of pliable material that may be fused by the application of heat.

After wire 34 with its fusible coating 36 is wound tightly around splice 26 for an area sufficient to completely cover ends 30, heat is applied thereto. Plastic is highly desirable because of its inherent quality of fusing upon itself and upon the splice 26 as well as the ends 30. When heat is so applied, the fusible material which may take many forms other than plastic, will run together to present a solid sleeve as shown in Fig. 2 at the uppermost end of seizing 32.

The wire 34 being tightly wound upon splice 28 will serve to reinforce the fused body and to hold the same in place rigidly upon splice 26. A smooth surface that is free from bulkiness is afforded in a manner not heretofore made possible by conventional types of splice seizures.

It is clear that all the above described desirable features taken together present a sling that will embody many advantages when placed in use. A strong, highly flexible and unbulky sling capable of many uses in handling loads of widely differing contours is present in the instant invention.

The particular manner of laying the splices taken with the type of seizing illustrated and described prevents unravelling and catching of loose ends on the work handled. The splice itself is extremely neat in appearance and hardly perceptible as a splice. The individual wires, strands and ropes not only in the body of the sling but in the loops and splices are each so interwoven as to bear equally the load and stresses imparted thereto. The alternate laying of the separate units and the precise manner in which the ropes are twisted presents a juxtaposition of parts in such manner as to decrease the usual wearing of the small wires of the cable by rubbing together during use of the sling.

Although the present invention has been described having reference to specific examples and applications, it is manifest that it is not desired to be limited thereto because obvious modifications will readily present themselves to those skilled in the art.

Having thus described the invention, what is claimed as new and desired to be secured by Letters Patent is:

1. A sling of the character described comprising a plurality of ropes laid up to present a cable forming the body of said sling; and at least one loop formed by bending one end of the body upon itself, said one end of the body being secured to the standing part of the body by a splice, said ropes of the end of the body being twisted upon the ropes respectively of the standing part of the body to form said splice.

2. A sling of the character described comprising a plurality of ropes laid up to present a cable forming the body of said sling; and at least one loop formed by bending one end of the body upon itself, said one end of the body being secured to the standing part of the body by a splice, said ropes of the end of the body being twisted upon the ropes respectively of the standing part of the body to form said splice, the direction of twist of all of said ropes within the splice being the same.

3. A sling of the character described comprising a plurality of ropes laid up to present a cable forming the body of said sling; and at least one loop formed by bending one end of the body upon itself, said one end of the body being secured to the standing part of the body by a splice, said ropes of the end of the body being twisted upon the ropes respectively of the standing part of the body to form said splice, the direction of twist of all of said ropes within the splice being opposite to the direction of lay of the ropes of said body.

4. A sling of the character described comprising a plurality of ropes laid up to present a cable forming the body of said sling, each of said ropes comprising a number of twisted strands; at least one loop formed by bending one end of the body upon itself, said one end of the body being secured to the standing part of the body by a splice with the ends of the strands adjacent said end of the body projecting laterally from the standing part of the body; and seizing circumscribing said splice adjacent said ends of the strands, said seizing having a material included in the formation thereof capable of fusing upon itself upon application of heat thereto.

5. A sling of the character described comprising a plurality of ropes laid up to present a cable forming the body of said sling, each of said ropes comprising a number of twisted strands; at least one loop formed by bending one end of the body upon itself, said one end of the body being secured to the standing part of the body by a splice with the ends of the strands adjacent said end of the body projecting laterally from the standing part of the body; and seizing circumscribing said splice adjacent said ends of the strands, said seizing having a material included in the formation thereof capable of fusing upon itself upon application of heat thereto, and a relatively stiff stiffening material.

6. A sling of the character described comprising a plurality of ropes laid up to present a cable forming the body of said sling, each of said ropes comprising a number of twisted strands; at least one loop formed by bending one end of the body upon itself, said one end of the body being secured to the standing part of the body by a splice with the ends of the strands adjacent said end of the body projecting laterally from the standing part of the body; and a wire seizing coiled about said splice adjacent said ends of the strands, said wire having a covering of material capable of fusing upon itself upon application of heat thereto.

7. A sling of the character described comprising a plurality of ropes laid up to present a cable forming the body of said sling, each of said ropes comprising a number of twisted strands; at least one loop formed by bending one end of the body upon itself, said one end of the body being secured to the standing part of the body by a splice with the ends of the strands adjacent said end of the body projecting laterally from the standing part of the body; and a wire seizing coiled about said splice adjacent said ends of the strands, said wire having a covering of material capable of fusing with the wire and that portion of the splice adjacent thereto, including said ends of the strands when heat is applied thereto.
